UNITED STATES PATENT OFFICE.

IRA A. PALMER, OF BAYARD, IOWA, ASSIGNOR OF ONE-HALF TO W. W. HIDLEBAUGH,
OF BAYARD, IOWA.

AUTOMATIC HEAD-LAMP CONTROL.

1,224,779.

Specification of Letters Patent. Patented May 1, 1917.

Application filed January 21, 1916. Serial No. 73,397.

To all whom it may concern:

Be it known that I, IRA A. PALMER, a citizen of the United States, residing at Bayard, in the county of Guthrie and State of Iowa, have invented new and useful Improvements in Automatic Head-Lamp Controls, of which the following is a specification.

This invention relates to automatic head-lamp controls, the object in view being to provide mechanism readily applicable to any present day type of automobile or motor car and adapted to be connected with a part of the steering mechanism, whereby the headlamps are turned to one side or the other as the steering wheels of the machine are turned, one of the principal objects of the present invention being to provide novel means whereby the up and down movement of the frame of the machine is automatically compensated for without interfering with or deranging the lamp turning mechanism.

A further object of the invention is to provide for an amplified movement of each of the headlamps in relation to the angles assumed by the steering wheels, so that the rays of light are directed to greater angles than the angles assumed by the steering wheels, this having been found advantageous in more fully illuminating the opposite sides of the road way especially in making turns along unfamiliar roads.

With the above and other objects in view, the invention consists in the novel construction, combination and arrangement of parts, as herein described, illustrated and claimed.

In the accompanying drawings:

Figure 1 is a front elevation illustrating the automatic lamp control of this invention applied to an automobile.

Fig. 2 is a side elevation of the same partly in section.

Fig. 3 is an enlarged vertical sectional view of the lamp turning mechanism.

Fig. 4 is a horizontal section on the line 4-4 of Fig. 3.

Fig. 5 is an elevation of the chain and clip.

Referring to the drawings 1 designates the headlamps of an automobile, 2 the lamp holding brackets and 3 substantially vertical lamp posts which in carrying out the present invention are mounted to turn on vertical axes so that the rays of light may be thrown straight ahead or to one side or

the other as may be required from time to time:

4 designates a bearing in the form of a tubular body having fastened thereto a U-shaped clip 5 to the upper and lower extremities 6 of which are connected the inner 60 reduced and threaded extremities 7 of a pair of superimposed metal plates or strips 8, the same being adjustable in the direction of their length by means of nuts 9. The opposite ends of the plates or strips 8 are 65 formed with holes to receive a bolt 10 which is inserted therethrough and has a nut 11 threaded thereon. The clip thus formed is adapted to be placed around one of the side bars of the frame so that the bearing 70 4 may be set at any desired distance from and in front of the radiator of the machine according to the desire of the owner of the machine.

Fixedly related to the upper end of the 75 bearing 4 is the cup-shaped bottom section 12 of a gear casing or housing, the same embodying in addition to the bottom section 12, an upper cap section 13 which has a detachable threaded connection at 14 with the 80 base section 12. Fast on the lower end of each lamp post 13 is a central spur pinion 15 and just above the pinion 15 is an enlarged circumferential flange or collar 16. The lower section 12 of the gear housing is 85 formed with internal teeth 17 with which mesh planetary pinions 18 which also mesh with the central gear or pinion 15. Three of such planetary pinions 18 are illustrated but more or less may be employed as found 90 expedient. These planetary pinions are journaled upon and carried by an oscillatory spider or head 19 having a downwardly extending shaft 20 which extends below the bearing 4 where it is reduced and squared 95 as indicated at 21 to fit into a correspondingly shaped hole in a lamp turning arm 22, the latter being secured to the shaft 20 by means of a nut 23 or by any equivalent means.

The shaft 20 is centrally and longitudinally bored from the upper end thereof, said bore extending also through the head or spider 19 and being adapted to receive a central spindle 24 extending downwardly 105 from the lower face of the central gear or pinion 15 which is fast on the lamp post 3.

Connected to the lower end of the arm 22

100

2
by means of a bolt 25 is a longitudinally extensible rod or member comprising an outer tubular section 26 and an inner relatively slideable section 27, the outer section 26 carrying a set screw 28, by means of which the rod as a whole may be lengthened and shortened to adapt the device as a whole to be set to suit any particular automobile. At its extremity, the longitudinally extensible rod has connected thereto the terminal link 29 of a parallel link chain 30, said chain having at its lower extremity a forked clip 31 which is pivotally connected to the adjacent terminal link of the chain by means 15 of a pin or bolt 32 the axis of which is parallel to the rod 33 which connects the knuckle arms of the ordinary steering gear. The chain 30 may flex in a fore and aft direction but is inflexible in a transverse direction. Therefore, when the rod 33 is moved in a substantially longitudinal direction, it necessarily carries with it the overhanging extremity of the longitudinally extensible rod 26 thereby turning also the arm 20 23 and imparting a corresponding turning movement to the shaft 23 of the spider or head 19.

As the head 19 turns, the pinions 18 are carried around thereby and mesh simultaneously with the internal gear or teeth 17 and the teeth of the central pinion 15. This causes the lamp post 3 to turn through a greater number of degrees than the shaft 20 and this amplified movement of the post 3 30 causes the lamp supported and carried thereby to swing through a greater arc than the front steering wheels of the machine. Therefore, the side of the road is illuminated throughout a greater zone than 35 would be the case where the lamp was turned the same number of degrees as the front steering wheels of the machine in accordance with the usual practice.

The chain 30 takes care of the up and down movement of the frame in relation to the axle and also in relation to the steering knuckle arm connecting rod 33. Therefore, there can be no injury to the lamp turning mechanism all parts of which are located above the plane of the front axle of the machine so as to prevent injury by contact with the ground or obstructions when bad roads and other difficult places are being negotiated by the machine.

By reason of the construction shown and described, the apparatus is applicable to any machine without the necessity of drilling holes in the frame or removing rivets and the like. Furthermore, the apparatus is adjustable to machines of different styles and sizes. The lamps may be set close up to or at any desired distance from the front of the radiator according to the taste or desire of the manufacturer and owner of the car.

Having thus described my invention, I claim:

In automatic lamp control, the combination of a fixed lamp-supporting bearing having an internal gear face, a substantially vertical lamp post adapted to turn on its longitudinal axis, a gear fast on said post, an oscillatory shaft mounted in said bearing and having a pinion carrying head, planetary gears on said head meshing with said internal gear face and pinion to produce an amplified turning movement of the lamp post, and operating connections between said oscillatory shaft and the steering knuckle arm connecting rod of a vehicle.

In testimony whereof I affix my signature in presence of two witnesses.

IRA A. PALMER.
